ABSTRACT

A separating device readily separates a desired number of sheets of paper in bundle form from a pile of paper sheets placed on a pallet or skid without disturbing the orderly piled-up bundle. The device comprises a nozzle made in a flat, palm-like form by which a compressed air is ejected into the boundary portion between the paper bundle and the paper pile and diffused uniformly over the entire area of the boundary portion to provide an air separation layer. The nozzle has guides for effecting diffusion of the compressed air.

DEVICE FOR SEPARATING A BUNDLE OF PAPER

BACKGROUND OF THE INVENTION

The present invention relates to a device for separating a desired number of sheets of paper in bundle form from a pile of paper sheets placed on a pallet or skid and more particularly to a device for separating a bundle of paper which is provided with a nozzle for ejecting a compressed air into the boundary portion between the paper bundle and the paper pile.

In the case where bundles of sheets of paper are handled as in a paper manufacturing, cutting, printing, bookbinding companies, etc. repeated operations have to be carried out to separate a desired number of sheets of paper (i.e. a paper bundle of a desired thickness) from a pile of paper. A common procedure employed in conducting such operation is that an end portion of paper bundle of a required thickness is grasped by the hand, the end portion is then lifted violently as if to throw the paper bundle upward and immediately lowered to provide separation between the paper bundle in the hand and the rest of the paper pile, and the paper bundle is thereafter slid on the pile for removal. However, this procedure has the following disadvantages:

1. In the case of a paper bundle of a large thickness, the great weight of paper requires much effort to lift it and it is difficult to provide a separated layer.
  2. The sheets of paper slip on one another and the orderly piled-up sheets tend to be disturbed.
  3. The above-mentioned handling requires much skill.
- The present invention provides a novel device for carrying out the procedure described above.

SUMMARY OF THE INVENTION

An object of the present invention is to provide a device by which a bundle of sheets of paper can be readily separated from a paper pile.

Another object of the present invention is to provide a device for separating a bundle of paper which is lightweight and easy to handle.

Another object of the present invention is to provide a device for separating a bundle of paper by which, when a compressed air is ejected into a boundary portion between the paper bundle and the rest of paper pile, the compressed air can be diffused rapidly and uniformly over the entire area of the paper surfaces at the boundary portion.

Still another object of the present invention is to provide a device by which the above-mentioned separating procedure can be carried out readily irrespective of the thickness (i.e. weight) of the paper bundle without disturbing the orderly piled-up paper bundle.

In accordance with the present invention, a device for separating a bundle of paper comprises an air inlet for feeding in a compressed air, an expansion chamber in communication with the air inlet and a nozzle in communication with the expansion chamber, the nozzle being formed in a flat palmlike shape in appearance and provided in its interior with guides for enlarging the air passage progressively toward the end of the nozzle.

The paper bundle separating device of this invention which comprises the air inlet, expansion chamber and a flat, palmlike nozzle in communication with one another is very simple in structure, lightweight and compact and ensures perfectly trouble-free operation.

When a paper bundle is to be separated from a pile of paper sheets by employing the device of the invention, the compressed air discharged beneath the boundary surface of the paper bundle is at first retained in the boundary portion due to the weight and flexibility of the paper bundle and forces the opposite boundary surfaces outward with increasing pressure until the air is diffused almost uniformly between the entire area of the surfaces. Such diffusion is achieved within a very short period of one second after the initiation of air discharge. The diffused air serves as a separation layer between the paper

bundle and the underlying paper pile to keep the former suspended on the thin air layer. Due to the fact that the paper bundle has a weight of its own and that the separation layer is progressively extended over the entire area in the boundary portion without resulting in partial escape of the air, possible vibration of the paper which would be attributable to suction effect produced by the high speed ejection of compressed air can be precluded.

When a thin air layer serving as separation layer is formed over the entire area at the boundary, the friction force to be exerted between the lowermost surface of paper bundle and the uppermost surface of the paper pile is eliminated. Accordingly, the paper bundle can be moved on the paper pile with extreme ease and without applying a great force. Thus, the present invention ensures easy and trouble-free handling operation irrespective of the thickness (i.e. weight) of the paper bundle, eliminating the need of skilled operators. Because the paper bundles are handled readily, slippage of sheets of paper no longer takes place, nor will the orderly piled-up sheets be disturbed.

It is possible to apply the present device to an automatic paper bundle separating apparatus in feeding bundles of paper to an automatic packaging machine or the like for automatic separation of paper bundles.

BRIEF DESCRIPTION OF THE DRAWING

FIG. 1 is a perspective view showing an embodiment in accordance with the present invention;

FIG. 2 is a side elevation in vertical section showing the embodiment in FIG. 1 and taken along the line II-II in FIG. 3;

FIG. 3 is a plan view in cross section taken along the line III-III in FIG. 2; and

FIGS. 4 (a), (b) and (c) are perspective views showing a paper bundle separating device in accordance with the present invention as it is being used.

DESCRIPTION OF THE PREFERRED EMBODIMENT

Referring to FIGS. 1 to 3, designated at 1 is a frame provided with an air inlet 2 and an expansion chamber 3 in its interior. The air inlet 2 is connected with an air duct 4 for supplying a compressed air from a compressed air source. The expansion chamber 3 is communicated with a nozzle 5. The compressed air introduced into the frame 1 through the air inlet 2 is allowed to expand in the expansion chamber 3 which serves to eliminate pulsating variations in the air pressure. As shown in the drawing, the nozzle 5 is formed in a flat, palmlike shape in appearance, the structure of the nozzle being such that it can be readily inserted between the paper pile and paper bundle to be separated therefrom and that the air can be prevented from flowing out through the openings which are formed on the opposite sides of the nozzle 5 when it is placed in the above-mentioned position. Disposed in the interior of the nozzle 5 are guides 6 for increasing the sectional area of the air passage toward its end, the guides 6 serving to diffuse the air stream into the opening between the bundle and the underlying pile at a substantially uniform flow rate when it is discharged from the nozzle 5. Designated at 7 is a push button switch adapted to open or close an unillustrated valve provided in the air inlet 2 to open or close the air inlet.

Although the embodiment illustrated has a structure in which the nozzle 5 is joined with the frame 1 in L-shaped form and the air duct 4 is connected to the upper portion of the frame 1, the nozzle 5 may be disposed in alignment with the air inlet 2 and expansion chamber 3, instead of being provided at right angle relative to the frame 1. In this case, the opening for the air inlet 2 may be formed in the rear of the frame 1 in communication with the air duct 4.

To separate a bundle of paper from a paper pile by employing the device described above, a corner 10 of a desired thickness of paper bundle 9 is gripped and lifted manually off a paper pile 8 placed on a pallet 11 to form an opening 75 between the bundle and the pile as shown in FIG. 4 (a). The

nozzle 5 is inserted into the opening so as to be located between the separated layers of paper as shown in FIG. 4 (b) and the push button switch 7 is depressed to open the air inlet 2. Compressed air is now introduced between the separated layers through the nozzle 5. Thus, by inserting the nozzle 5 into the space between the paper bundle and the rest of the paper pile so as to cause the air to eject toward the center of the under face of the paper bundle, the pressure of the air discharged through the nozzle 5 progressively increases to lift the paper bundle against the weight of the paper, with the result that an air layer serving as a separation layer is formed over the entire area of the boundary portion. The air layer is retained effectively with continuous supply of air. As already described the time required to form the separation layer is a very short period of within one second.

Since the friction force to be produced on the lowermost surface of the paper bundle is reduced nearly to zero while the paper bundle 9 is kept suspended, the paper bundle 9 can be pushed forward and thereby slid off the paper pile for separation irrespective of the weight of the paper bundle 9 as seen in

FIG. 4 (c).

We claim:

1. A device for insertion into one edge of a bundle of paper to separate the bundle and float the upper separated segment of the bundle on the lower segment for removal of the upper segment comprising, a body having an expansion chamber therein, an air inlet into the expansion chamber an an air outlet from the expansion chamber, and a separate flat nozzle in communication with the air outlet and connected to and projecting from one end of the body at a right angle with respect to the body for insertion between selected sheets of the bundle to separate the bundle into predetermined segments whereby the body provides a stop to engage an edge of the separated paper segment when the nozzle is inserted into a bundle and wherein said nozzle diverges from its connection to the body, and there are dividers within the nozzle separating the nozzle into a plurality of outwardly diverging air passages all of which air passages are inclined in one direction.
